PATTERN TRACING APPARATUS

Bernice H. Anderson, Rte. 1, Box 818, Excelsior, Minn.
Filed July 2, 1958, Ser. No. 746,240
5 Claims. (Cl. 101—26)

This invention relates to pattern tracing apparatus. More particularly, it relates to a needle structure designed for tracing patterns upon fabrics where several thicknesses or fabrics are to be cut to the same pattern.

In dress making and other forms of needlecraft, it is often necessary to trace a pattern upon several pieces of fabric in order to indicate upon each piece the location of various components of the dress or other garment such as a pocket, button, buttonhole, pleat, etc. In most garments such components are duplicated and positioned in corresponding locations at the left and right hand sides of the garment and hence it is important that the locations of these components be accurate. Considerable time and effort is expended in tracing the patterns upon each such piece of material and yet this has always heretofore been considered necessary. My invention is designed to enable the user to complete the entire operation by merely tracing the pattern once with my pattern tracing needle.

In cutting patterns in dress making and the like, it is generally necessary that several thicknesses or pieces of fabric must be cut to the same pattern and it is conventional in so doing to place the pattern upon the upper layer or thickness of the fabrics and cut several thicknesses to the same pattern insofar as is possible. Several thicknesses or layers of the fabric are cut simultaneously in order to conserve time and effort by avoiding the necessity of cutting the pattern on each layer or thickness of the fabric individually. It is well recognized however, that in so doing the pattern upon the lower pieces of fabric differ somewhat from the pattern cut from the upper sheet or layer of the fabric because in cutting the fabrics the lower layers tend to shift relative to the upper layers, with the result that the patterns cut from the sheets of fabric are not accurate. My invention is designed to overcome this disadvantage by simultaneously tracing a pattern upon a number of layers of fabric so that it will be a simple matter to cut out the pattern from each sheet or layer of fabric individually.

It is a general object of my invention to provide a novel and improved pattern tracing apparatus of simple and economical construction and operation.

A more specific object is to provide novel and improved pattern tracing apparatus which may be utilized either manually or in combination with a sewing machine to quickly and easily trace a pattern upon several layers of fabric in such a way that the pattern will be equally accurate upon all layers of fabric.

Another object is to provide a simple and inexpensive pattern tracing device which will mark each of several layers of fabric simultaneously and indelibly in a far more accurate manner than has heretofore been possible.

Another object is to provide a simple pattern tracing device utilizing a marking fluid which is so constructed that the reservoir containing the marking fluid may be readily removed and a new reservoir with a fresh supply of marking fluid applied thereto.

These and other objects and advantages of my invention will more fully appear from the following description made in connection with the accompanying drawings wherein like reference characters refer to the same parts throughout the several views and in which:

FIG. 1 is a side elevational view of one embodiment of my invention with portions thereof broken away in sections to illustrate the construction thereof;

2

FIG. 2 is a plan view of the reservoir utilized in conjunction with my pattern tracing needle; and

FIG. 3 is a side elevational view of the reservoir with portions broken away to more clearly show the construction of the upper wall thereof.

One embodiment of my invention as shown in FIGS. 1-3 may include a hollow needle indicated generally by the numeral 5 which has a hollow inside and pointed lower end 6 and a head 7 at its upper end which is flat 10 at one side 8 to adapt the same to be received within the needle chuck 9 of a sewing machine. The chuck 9 is provided with a tightening screw 10 which is adapted to engage the flat side 8 of the needle to hold the same tightly therein.

15 The needle 5 is provided with a marking fluid inlet 11 at its medial portions adjacent the head 7 and with a marking fluid outlet 12 at its outside adjacent its lower pointed end 6. It will be noted that the outlet 12 opens at the outside of the needle so that the marking fluid 20 may be wiped off the needle when passing through several layers of fabric and thereby apply the marking fluid to each of the layers of fabric.

A reservoir 13 formed of material which is flexible and resilient such as a high impact plastic is provided for 25 containing the marking fluid which is indicated generally by the numeral 14. As shown, the reservoir is cylindrical in shape and has walls 13a which are flexible and resilient and sufficiently soft to seal around the needle 5 when the needle pierces the upper and lower walls of the reservoir as shown in FIG. 1. Thus, escape of marking fluid around the needle is prevented by the soft material from which the wall structures of the reservoir 13 are made.

The upper wall of the reservoir 13 is so formed as to have two relatively thin areas 15 and 16. The thin area 35 15 is centrally disposed and is so formed in order to facilitate insertion of the needle 5 therethrough. The thin area 16 is more laterally disposed and is provided for the sole purpose of facilitating piercing of the upper wall by the needle 5 or some other sharp object if it is 40 found necessary in order to permit the marking fluid to descend through the needle 5 to the marking fluid outlet 12. It is believed that ordinarily the upper wall structure need not be pierced at the thin area 16 for under normal circumstances capillary action will be sufficient 45 in the needle 5 to cause the marking fluid to descend and maintain a constant supply of marking fluid at the outlet 12. If it is found however, that the rate of consumption of marking fluid at the outlet 12 is so great that capillary action will not provide an ample supply of marking fluid at that point, then the upper wall may be pierced 50 at the thin area 16 in order to permit air to enter the reservoir at that point.

It will be noted that the marking fluid inlet 11 is disposed within the confines and in communication with the 55 interior of the reservoir 13 so that the marking fluid may enter at this inlet and descend through the needle 5 to be disseminated or applied at the marking outlet 12 as the needle passes through the several layers of fabric. If and when the reservoir 13 is emptied it can be readily 60 replaced by sliding it downwardly over the lower end of the needle 5 and substituting therefore a new capsule filled with marking fluid by merely forcing the pointed end 6 of the needle 5 through the thin area 15 and through the lower wall structure of the reservoir 13 until 65 it reaches the position relative to the reservoir shown in FIG. 1.

In use, the several layers of fabric may be placed upon a flat surface with the pattern superimposed thereon and the pattern then traced by piercing therewithal with the 70 needle 5 to such an extent that the lower pointed end 6 of the needle will pass through each layer of fabric.

This of course may be done manually but it is preferred to mount the needle 5 in the chuck 9 of a sewing machine as shown in FIG. 1 and then operating the sewing machine so as to trace the pattern with the rapidly rising and descending needle 5 in the same manner as would be followed in a sewing operation. As the needle 5 passes through the fabrics a small amount of marking fluid will be wiped off upon each layer of fabric so that the pattern will be accurately and clearly traced upon each layer of the fabric. Each layer of fabric will wipe past the marking fluid outlet 12 and in so doing will pick up a small amount of the marking fluid with the result that the pattern will be traced thereon.

From the above it can be seen that I have provided a uniquely simple, inexpensive and effective pattern tracing device which will trace patterns upon several layers of fabric simultaneously in a highly improved manner. The use of this pattern tracing device obviates the inaccuracies heretofore experienced in attempting to simultaneously cut a plurality of layers of fabric while following a pattern superimposed upon only the upper layer of fabric.

It will, of course, be understood that various changes may be made in the form, details, arrangement and proportion of the parts without departing from the scope of my invention which consists of the material shown and described herein and set forth in the appended claims.

What is claimed is:

1. A pattern tracing apparatus comprising a sewing machine, a hollow needle mounted on said machine, said needle having a marking fluid inlet intermediate its ends and having a lower end with a marking fluid outlet disposed adjacent thereto, and a marking fluid containing reservoir formed of flexible and resilient material and mounted on said needle said reservoir having its interior connected in fluid communication with the fluid inlet of said needle whereby marking fluid will pass through said needle from said reservoir and be applied to a fabric when the latter is pierced by the lower end of said needle.

2. The structure defined in claim 1 wherein said needle extends through said reservoir and said marking fluid inlet of said needle is disposed within the interior thereof.

3. The structure defined in claim 1 wherein said needle extends through said reservoir in piercing relation and is longitudinally slideable relative thereto to make said reservoir readily removable and replaceable by a similar reservoir.

4. A pattern tracing apparatus comprising a sewing machine including a needle-receiving head, a hollow needle having its upper end secured within said head, said needle having a marking fluid inlet intermediate its ends and having a lower end with a marking fluid outlet disposed adjacent thereto, a marking fluid containing reservoir formed of flexible and resilient material and mounted on said needle intermediate the ends thereof, and said reservoir having its interior connected in fluid communication with the fluid inlet of said needle whereby marking fluid will pass through said needle from said reservoir and be applied to a fabric when the latter is pierced by the lower end of said needle.

5. A fabric marking device for use with sewing machines having needle receiving heads, said device comprising a hollow needle adapted to have its upper end secured within the needle-receiving head of such a sewing machine, said needle having a marking fluid inlet intermediate its ends and having a lower end with a marking fluid outlet disposed adjacent thereto, a marking fluid containing reservoir formed of flexible and resilient material and mounted on said needle intermediate the ends thereof, and said reservoir having its interior arranged in fluid communication with the fluid inlet of the needle whereby marking fluid will pass through said needle from said reservoir and be applied to a fabric when the latter is pierced by the lower end of said needle.
